UNITED STATES PATENT OFFICE.

JOHN M. GANTVOORT, OF BEACON, NEW YORK.

BAKER'S OVEN.

Application filed February 9, 1921. Serial No. 443,591.

To all whom it may concern:

Be it known that I, JOHN M. GANTVOORT, a citizen of the United States of America, residing at Beacon, in the county of 5 Dutchess and State of New York, have invented certain new and useful Improvements in Bakers' Ovens, of which the following is a specification:

My invention relates to bakers' ovens, 10 and particularly to traveling ovens, the object of my invention being to provide a baker's installation comprising a battery of relatively small independent traveling oven units with a common feed and discharge 15 mechanism therefor.

Traveling ovens are commonly of very large capacity with relatively slow progress of the shelf-supporting chains through the oven. Loading of the shelves at one end 20 of the oven, and their discharge of the baked goods at the other end of the oven, are practically continuous operations, inasmuch as the time consumed in a single traverse of the baking chamber is sufficient 25 to complete the baking operation. While such an installation is efficient when in good working condition, it entails the serious draw-back that upon a break-down of any portion of the installation the entire 30 oven is thrown out of operation and the output of the plant correspondingly reduced. Moreover, the construction of such a traveling oven involves a very large investment.

35 The underlying thought of the present invention consists in substituting for a single large oven installation of this type, a battery of relatively small oven units, each independent of the other, and capable of 40 independent operation, the battery as a whole, however, affording, when the unit group is sufficiently extended, a capacity equal to that of the usual large traveling oven. Associated with the oven battery 45 are feed and discharge devices common to all of the oven units of the group. The battery preferably comprises a unit in excess of the number required under normal 50 operating conditions, so that in the event of break-down of any one of the operating units, the excess unit may be at once placed in service during repairs without interrupting or diminishing the output of the plant. 55 Whether or not an excess unit is included in the battery, obviously, failure of one unit does not completely cripple the plant.

Again, a unit system of this type has the great advantage over single large ovens, that it permits different oven conditions in the several oven units for several types of baked 60 goods—an advantage of marked value to the small baker, who produces goods of different character. In addition to this flexibility of operation, which permits more or less of the units to be utilized with varying 65 demand, a new unit may be readily added to the installation, at relatively small expense, to increase the capacity of the plant, while the same feed and discharge devices 70 may be used with no other expense than the insertion of an added length in the conveyor belts.

It may be further pointed out that a unit installation of this type is well adapted to a change-over from existing peel-oven installations into multi-unit traveling oven installations, the latter possessing greater output capacity for a given floor area occupied thereby, as well as greater economy 80 and convenience of operation.

It will be obvious from the foregoing that the invention resides in a broad underlying conception rather than in any particular detail of construction. With this understanding the invention has been presented more or less diagrammatically in the accompanying drawings in which—

Fig. 1 is a vertical section through an oven unit to which my invention is applied 90 in one form; and

Fig. 2 is a front elevation of a battery of such oven units.

While the number of oven units may be varied to meet the output capacity required 95 of a plant, I have here illustrated a battery of four units, 3, 4, 5 and 6, arranged side by side in alignment, each having a baking chamber 7 in which travel the chains 8 upon which the baking shelves 9 are supported. The manner of heating the oven 100 units may be varied, and I have indicated only by way of example, a group of Perkins tubes 10 for each unit extending into a heating chamber 11 below the baking chamber 7 from the fire box 12, to which access is had from the rear of the unit through the fire door 13. The air heated by the tubes 10 rises from the chamber 11, through the passage 14 to the inlet 15 at 105 the top of the oven chamber, controlled by a damper 16, and passes through the oven chamber in contact with the baking goods, 110

eventually returning to the chamber 11, through the down-comer passage 17, and port 18. Each chain travels around sprockets 19 and 20, one of which, viz, 20, is mounted on a shaft 21 extending the length of the battery of oven units and driven by a gear 22 at one end of the battery.

At the front of each oven unit I provide a metallic bay 23, projecting beyond the front wall 24, and provided with arcuate sliding doors 25 and 26, which normally close the feed and discharge openings 27 and 28 to the baking chamber. The front sprocket 19 is so located that the chains 15 bring the baking shelves 9 into a position relatively close to the inner face of the bay to facilitate the loading and unloading operations. A guide platform 29 may be arranged on the inner face of the bay at the lower margin of the feed opening 27 to support the goods as they pass to the shelves during the loading operation. Similarly, 20 a tipping lug 30 may be provided to temporarily halt the shelves and tip them to discharge position as they reach the discharge port 28 during the discharging operation.

Extending transversely in front of the battery of oven units are two fixed supports 31 and 32, one adjacent the lower margin of the feed openings 27, and the other adjacent the lower margin of the discharge openings 28. Passing over these supports are endless conveyors 33 and 34 which serve the oven battery. The conveyor 33 brings to loading position, before each oven of the battery, the goods 35 to be baked, while the conveyor 34 receives and removes the baked goods 36. The conveyor 33 preferably extends from the oven battery to a point at which it may be conveniently loaded with the goods ready to enter the ovens, for example, to the proofing room. The discharge conveyor 34 extends from the oven battery to a suitable cooling room, where the baked goods are discharged and permitted to cool under proper conditions.

Any suitable means may be provided for advancing the feed belt 33 intermittently, or 50 for halting its travel momentarily during the transfer of the goods from the conveyor to the shelves within one of the oven units. During the loading operation, the chains 8 for the shelves may also be similarly halted 55 intermittently to bring the successive shelves 9 to stationary position adjacent the guide 29, so that the goods 35 may be transferred by any suitable means, from the belt 33 to the shelf. The travel of the chains 8 may 60 be so slow that an actual halt of the shelf in loading position is not necessary. When a halt is desired, however, it may be obtained by driving the chains 8 for each of the ovens independently, for example, by a switch-controlled electric motor instead of from the

common drive shaft 31, although any suitable clutch device may be provided in the connection between the drive shaft and the sprocket 20—for instance, a one-way drive connection—which permits the shaft 21 to 70 continue its rotation, while the chains 8 are halted. Inasmuch as such mechanisms are of common construction, they have not been illustrated. The detent 30 for tilting the shelves for discharge is pivoted and may be 75 moved out of detaining position during the baking operation, so that the shelves travel freely past it.

In an installation of the present type, the loading and unloading operations may take 80 place practically simultaneously in one unit, while in the remaining units of the battery baking operations are in progress, or one unit may be loaded while another unit is discharged. It is thus possible for a single operative to tend a relatively large number of units, in which the baking operations take 85 place in sequence. Moreover, the installation permits goods of different character to be baked in the different units, while at the 90 same time making use of the common feed and discharge conveyors 33 and 34. Similarly, the advantages of a common feed and 95 discharge arrangement are available for goods requiring different baking conditions; and the temperature and moisture conditions in the several units may be varied to 100 meet these different requirements. Again, the shelves for the several units may be of different character; for instance, the shelves 105 of one unit may be suitable for baking pan bread, while the shelves of an adjacent oven are suitable for the baking of hearth bread; while the shelves and general conditions in another oven may be adapted to the baking 110 of cakes and pastry. It is thus obvious that the installation affords a flexibility of 115 operation and a variation of baking conditions in the several ovens suitable for various types of baked goods, while for all of the ovens the feed and discharge devices are 120 equally serviceable.

While I have indicated some of the advantages and utilities of construction, as well as suitable embodiment of the invention, various modifications will occur to those skilled in the art which embody the underlying thoughts of what I claim as my invention.

I claim—

1. In a baker's installation, a battery of juxtaposed ovens having substantially aligned bays projecting from one end of the ovens, traveling supports within the ovens, baking shelves carried thereby and entering said bays during portion of their travel, and entry and discharge openings in said bays.

2. In a baker's installation, a battery of juxtaposed ovens having substantially 130

aligned bays projecting from one end of the ovens, traveling supports within the ovens, baking shelves carried thereby and entering said bays during portion of their travel, and 5 entry and discharge openings in said bays in combination with traveling conveyors common to said battery of ovens and arranged respectively adjacent the entry and discharge openings in the bays, for the purpose specified.

3. In a baker's oven, a baking chamber having a bay at one end, chains arranged in

said chamber and projecting into said bay, baking shelves supported on said chains, a door opening in said bay, a conveyor arranged in front of said bay and traveling transversely thereto and adapted to present goods to be baked at said door for the transfer therethrough transversely to the direction of travel of said conveyor to a baking shelf within the bay.

In testimony whereof I have signed my name to this specification.

JOHN M. GANTVOORT.
